(57) **CLAIM**

The ornamental design for a sleeve for frequency-steered sonar transducer assembly, as shown and described.

DESCRIPTION

FIG. 1 is a right top perspective view of a sleeve for frequency-steered sonar transducer assembly in accordance with an embodiment of the present invention;

FIG. 2 is a front view of the sleeve for frequency-steered sonar transducer assembly of FIG. 1;

FIG. 3 is a rear view of the sleeve for frequency-steered sonar transducer assembly of FIG. 1;

FIG. 4 is a right view of the sleeve for frequency-steered sonar transducer assembly of FIG. 1;

FIG. 5 is a left view of the sleeve for frequency-steered sonar transducer assembly of FIG. 1;

FIG. 6 is a top view of the sleeve for frequency-steered sonar transducer assembly of FIG. 1;

FIG. 7 is a bottom view of the sleeve for frequency-steered sonar transducer assembly of FIG. 1;

FIG. 8 a right top perspective view of the sleeve for frequency-steered sonar transducer assembly of FIG. 1, where the sleeve for frequency-steered sonar transducer assembly is attached to an example frequency-steered sonar transducer assembly;

FIG. 9 is a right top perspective view of a sleeve for frequency-steered sonar transducer assembly in accordance with another embodiment of the present invention;

FIG. 10 is a front view of the sleeve for frequency-steered sonar transducer assembly of FIG. 9;

FIG. 11 is a rear view of the sleeve for frequency-steered sonar transducer assembly of FIG. 9;

FIG. 12 is a right view of the sleeve for frequency-steered sonar transducer assembly of FIG. 9;

FIG. 13 is a left view of the sleeve for frequency-steered sonar transducer assembly of FIG. 9;

FIG. 14 is a top view of the sleeve for frequency-steered sonar transducer assembly of FIG. 9;

(Continued)

FIG. 15 is a bottom view of the sleeve for frequency-steered sonar transducer assembly of FIG. 9;
 FIG. 16 a right top perspective view of the sleeve for frequency-steered sonar transducer assembly of FIG. 9, where the sleeve for frequency-steered sonar transducer assembly is attached to an example frequency-steered sonar transducer assembly;
 FIG. 17 is a right top perspective view of a sleeve for frequency-steered sonar transducer assembly in accordance with another embodiment of the present invention;
 FIG. 18 is a front view of the sleeve for frequency-steered sonar transducer assembly of FIG. 17;
 FIG. 19 is a rear view of the sleeve for frequency-steered sonar transducer assembly of FIG. 17;
 FIG. 20 is a right view of the sleeve for frequency-steered sonar transducer assembly of FIG. 17;
 FIG. 21 is a left view of the sleeve for frequency-steered sonar transducer assembly of FIG. 17;
 FIG. 22 is a top view of the sleeve for frequency-steered sonar transducer assembly of FIG. 17;
 FIG. 23 is a bottom view of the sleeve for frequency-steered sonar transducer assembly of FIG. 17;
 FIG. 24 a right top perspective view of the sleeve for frequency-steered sonar transducer assembly of FIG. 17, where the sleeve for frequency-steered sonar transducer assembly is attached to an example frequency-steered sonar transducer assembly;
 FIG. 25 is a right top perspective view of a sleeve for frequency-steered sonar transducer assembly in accordance with another embodiment of the present invention;
 FIG. 26 is a front view of the sleeve for frequency-steered sonar transducer assembly of FIG. 25;
 FIG. 27 is a rear view of the sleeve for frequency-steered sonar transducer assembly of FIG. 25;
 FIG. 28 is a right view of the sleeve for frequency-steered sonar transducer assembly of FIG. 25;
 FIG. 29 is a left view of the sleeve for frequency-steered sonar transducer assembly of FIG. 25;
 FIG. 30 is a top view of the sleeve for frequency-steered sonar transducer assembly of FIG. 25;
 FIG. 31 is a bottom view of the sleeve for frequency-steered sonar transducer assembly of FIG. 25; and,
 FIG. 32 a right top perspective view of the sleeve for frequency-steered sonar transducer assembly of FIG. 25, where the sleeve for frequency-steered sonar transducer assembly is attached to an example frequency-steered sonar transducer assembly.

The dash-dash broken lines illustrate environmental structure and form no part of the claimed design.
